CLAIM

The ornamental design for a pendant lamp, as shown and described.

DESCRIPTION

FIG. 1 is a perspective view of a first embodiment of a pendant lamp showing my new design;

FIG. 2 is a right side elevation view thereof, the left side being a mirror image;

FIG. 3 is a front elevation view thereof, the rear being a mirror image;

FIG. 4 is a top plan view thereof;

FIG. 5 is a bottom plan view thereof;

FIG. 6 is a perspective view of a second embodiment of a pendant lamp showing my new design;

FIG. 7 is a right side elevation view thereof, the left side being a mirror image;

FIG. 8 is a front elevation view thereof, the rear being a mirror image;

FIG. 9 is a top plan view thereof; and,

FIG. 10 is a bottom plan view thereof.

The broken lines show environmental subject matter and form no part of the claimed design. The second embodiment is shown with symbolic breaks in height in FIGS. 6-8, and those portions of the article between the break lines form no part of the claimed design.
